CLAIM

The ornamental design for a front face of vehicle wheel, as shown and described.

DESCRIPTION

FIG. 1 is a perspective view of a front face of vehicle wheel showing my new design; it being understood that the broken lines are for illustrative purposes only and form no part of the claimed design;

FIG. 2 is a front elevational view thereof;

FIG. 3 is a perspective view of a second embodiment of a front face of vehicle wheel, it being understood that the broken lines are for illustrative purposes only and form no part of the claimed design; and,

FIG. 4 is a front elevational view of FIG. 3, it being understood that the broken lines are for illustrative purposes only and form no part of the claimed design.
